UNITED STATES PATENT OFFICE

2,295,043

ELECTRIC DISCHARGE LAMP

Arved Lompe, Berlin, and Martin Reger, Berlin-Charlottenburg, Germany, assignors to General Electric Company, a corporation of New York

Application June 27, 1940, Serial No. 342,780
In Germany June 28, 1939

3 Claims. (CL. 176—122)

The present invention relates to gaseous electric discharge lamps generally and more particularly the invention relates to such lamps of the positive column discharge type operating with low gas pressure, that is, with a luminous, diffuse positive column discharge.

Lamps of the above type provided with heated electrodes having a heater connected in series with the discharge to serve as series ballast therefore are now known in the art. We have observed that in such known lamps satisfactory operation is obtained only when the ohmic resistance of the electrode heater elements is higher than the resistance of the discharge column during the operation of the device. If this condition does not exist then the unavoidable fluctuations in the line voltage cause profound and undesired changes in the luminous output of the lamp. Such changes in luminous output are avoided by using large ohmic series resistances but such resistances dissipate a large proportion of the electrical energy supplied to the lamp and thus reduce the efficiency thereof.

The object of the present invention is to provide a highly efficient, self-contained electric lamp of the above type which is insensitive to fluctuations in line voltage. Still further objects and advantages of the invention will be apparent to those skilled in the art from the following detailed description thereof and from the appended claims.

The invention attains its objects by separating the electrodes in the lamp container such distance that at least sixty per cent of the voltage supplied to the apparatus is dissipated in the gaseous electric discharge between said electrodes and by connecting an iron-hydrogen resistor element in series with the electrode heaters and the discharge. The resistance of the iron-hydrogen element is not more than, and is preferably lower than, the total resistance of both the heater elements.

In a lamp embodying the invention the discharge current is limited primarily by the heaters for the electrodes, the comparatively low resistance of the iron-hydrogen resistor serving mainly to prevent excessive fluctuations in current density and in luminous output of the discharge. Thus, it is possible to separate the electrodes a greater distance than has been found practicable in prior lamps and to dissipate a greater proportion of the line voltage in the discharge resulting in a higher luminous efficiency.

Any of the means well known in the art may

be used for starting the discharge in the lamp. We prefer to connect the electrode heaters in series during the starting of the lamp by a lead external to the lamp containers. Preferably the lead contains a resistance and a switch, such as a thermostatic switch, for breaking the connection between the electrode heaters to start the discharge between the electrodes when said electrodes have been heated to a discharge supporting temperature. When desired, the current lead is cemented to the outer surface of the container or is covered with an electrically insulating material and is mounted inside the container and along the discharge path between said electrodes. The current lead thus serves as an auxiliary electrode having a capacitive effect.

In the drawing accompanying and forming part of this specification an embodiment of the invention is shown in a side elevational, partly sectional view.

Referring to the drawing the gaseous electric discharge lamp device comprises a tubular container 1 of vitreous material, such as glass or quartz. Said container is about 1 meter long, has an internal diameter of about 25 mm. and has a quantity 2 of mercury and a rare gas therein, such as argon, at a pressure of about 2 mm. An electrode 3, 4 consisting of a nickel shell 3 coated with an activating material, such as barium oxide, and a tungsten wire 4 mounted inside said shell 3 is mounted adjacent the ends of said container 1. Said electrodes 3, 4 are separated a distance such that when the operating current is about 100 milliamperes the voltage drop across the discharge path is approximately 155 volts. The heater wires 4 are connected in series with the discharge and an iron wire-hydrogen filled resistor element 5 (of known structure) is connected in series with one of said heaters 4. The element 5 is mounted outside the container 1 and inside of the hollow stem thereof. During the operation of the lamp the voltage drop across each of the heaters 4 is about 20 volts and the voltage drop across the resistor element 5 is about 25 volts.

The electrodes 3 are connected in series during the starting period by current lead 6 cemented to the outer surface of the container 1. Said lead 6 is co-extensive with said container 1 and has a capacitive effect which ionizes the gaseous filling in the container 1 to facilitate starting of the main discharge. A resistance 7 of about 1500 ohms is mounted in the hollow stem of the container 1 and is connected into said lead 6 in series with the electrode heaters 3. A bimetallic

switch 8 enclosed in a sealed glass chamber is connected into said lead 6 and is mounted inside said container 1 adjacent one of said electrodes 3, 4. The switch 8 is in the closed-circuit position when cold and moves to an open-circuit position when heated a predetermined time. Preferably the switch 8 is heated and thus is caused to move from a contact making to a contact breaking position by the heat from said electrodes 3, 4 when said electrodes 3, 4 have been heated to a discharge supporting temperature. When desired the switch 8 is mounted in the stem of the lamp housing the resistance 7 and is heated thereby. Said container 1 has cemented to each end thereof a metal base 9. The lamp is thus self contained and is operable on current sources of commercial voltage without the need for external auxiliary apparatus.

When the considerable ultra-violet radiation from the discharge is desired for use external to the lamp the container 1 is made of quartz or of an ultra-violet transmitting glass. When distinctly colored light is desired or when a higher luminous output or both is desired a luminescent material capable of emitting the desired radiation at the desired intensity is applied to the container 1. Luminescent glasses are also useful for this purpose.

Fluctuations in the light output of the lamp described above are reduced to a minimum when the voltage-current characteristic of the lamp is positive during the operation thereof. The lamp has a positive voltage-current characteristic when the tubular container 1 has an inside diameter of at least 30 mm., contains neon at a pressure of 2 mm. or less in addition to vaporizable mercury and has an operating discharge current of between 100 and 300 milliamperes.

The lamp described above is capable of operation on direct current or alternating current. On direct current operation only one of the electrodes need be provided with a heater element.

What we claim as new and desire to secure by Letters Patent of the United States is:

1. A lighting apparatus comprising in combination, an electric discharge lamp of the low-pressure, diffuse, positive column, luminous discharge type having spaced electrodes one of which is a thermionic electrode having a resistance heater which is connected in series with the discharge between said electrodes during operation of said device, the distance between said

electrodes being such that at least 60 per cent of the voltage of the current source on which said lamp is designed to operate is dissipated in the low-pressure discharge between said electrodes during operation, and an iron wire-hydrogen filled resistor connected in series with said resistance heater to minimize the effect of fluctuations in the supply voltage on the current density and the luminous output of the low-pressure discharge in said lamp.

2. A lighting apparatus comprising in combination, an electric discharge lamp of the low-pressure, diffuse, positive column, luminous discharge type having spaced electrodes one of which is a thermionic electrode having a resistance heater which is connected in series with the discharge between said electrodes during operation of said device, the distance between said electrodes being such that at least 60 per cent of the voltage of the current source on which said lamp is designed to operate is dissipated in the low pressure discharge between said electrodes during operation, and an iron wire-hydrogen filled resistor connected in series with said resistance heater to minimize the effect of fluctuations in the supply voltage on the current density and the luminous output of the low-pressure discharge in said lamp, the resistance of said iron wire-hydrogen resistor being at most equal to that of said resistance heater.

3. A lighting apparatus comprising in combination, an electric discharge lamp of the low-pressure, diffuse, positive column luminous discharge type having therein mercury, neon at a pressure of about 2 millimeters and spaced electrodes one of which is a thermionic electrode having a resistance heater which is connected in series with the discharge between said electrodes during operation of said device, the distance between said electrodes being such that at least 60 per cent of the voltage of the current source on which said lamp is designed to operate is dissipated in the low pressure discharge between said electrodes during operation, and an iron wire-hydrogen filled resistor connected in series with said resistance heater to minimize the effect of fluctuations in the supply voltage on the current density and the luminous output of the low-pressure discharge in said lamp.
